(57) **CLAIM**

The ornamental design for a drywall compound applicator, as shown and described herein.

DESCRIPTION

FIG. 1 is a perspective view of the drywall compound applicator showing my new design;

FIG. 2 is a side view in elevation of the drywall compound applicator shown in FIG. 1, with the front of the drywall compound applicator facing to the left of the page;

FIG. 3 is a side view in elevation of the drywall compound applicator shown in FIG. 1, with the front of the drywall compound applicator facing to the right of the page;

FIG. 4 is a view in elevation showing the front of the drywall compound applicator;

FIG. 5 is a view in elevation of the back of the drywall compound applicator;

FIG. 6 is a plan view of the top of the drywall compound applicator with the front facing downwardly; and,

FIG. 7 is a plan view of the bottom of the drywall compound applicator with the front facing downwardly.

The broken lines shown in FIGS. 1, 2 and 3 are included for the purpose of illustrating portions of the drywall compound applicator that form no part of the claimed design.
